STENCIL PRINTING MECHANISM

Ward Thorne, Westport, Conn., assignor, by
means assignments, to Linen Guild, Inc., New
York, N. Y., a corporation of New York

Application April 11, 1941, Serial No. 388,017

18 Claims. (Cl. 101—123)

The present invention relates to stencil printing mechanism and embodies, more specifically, an improved form of stencil printing device wherein stationarily located material to be printed upon is traversed by a printing mechanism that is advanced periodically and located automatically in successive printing positions. A device of this character is shown and described in the application of Wierk and Montague Serial No. 319,856 and the present invention embodies certain structural and operating improvements upon the foregoing mechanism.

More specifically, an object of the present invention is to provide an improved driving mechanism by means of which the movements of the stencil mechanism may be effected with precision and alacrity.

A further object of the invention is to provide an improved device by means of which the movable stencil carriage may be located accurately in a series of printing positions.

Yet another object of the invention is to provide an improved stencil operating mechanism by means of which the movements of the stencil with respect to the material to be printed may be effectively controlled.

A further object of the invention is to provide an improved mounting mechanism for the carriage upon which the carriage is mounted, by means of which the carriage may be located transversely of its direction of movement.

A further object of the invention is to provide an improved color applying mechanism by means of which the application of color to the material to be printed is accomplished effectively.

The foregoing objects are attained by means of fluid driving mechanism for actuating not only the movement of the carriage along the material to be printed but also the raising and lowering of the stencil frame and the locating mechanism by means of which the carriage is located in successive printing positions. Further structural improvements are embodied that will be described in greater detail hereinafter and that attain the objects hereinabove recited, as well as other objects that will be apparent to those skilled in the art upon reading the following specification in connection with the accompanying drawings, wherein:

Fig. 1 is a plan view of a machine constructed in accordance with the present invention.

Fig. 2 is a view in side elevation, partly broken away and in section, showing the device of Fig. 1.

Fig. 3 is a view in longitudinal section, taken

on the line 3—3 of Fig. 1 and looking in the direction of the arrows.

Fig. 4 is an enlarged detail view, showing a part of the carriage moving mechanism of Fig. 2.

Fig. 5 is a view in section, taken on the line 5—5 of Fig. 4 and looking in the direction of the arrows.

Fig. 6 is an enlarged view in section, taken on line 6—6 of Fig. 1 and looking in the direction of the arrows.

Fig. 7 is a view in section, taken on the line 7—7 of Fig. 4 and looking in the direction of the arrows.

Fig. 8 is an enlarged view in section, taken on the line 8—8 of Fig. 1 and looking in the direction of the arrows.

Fig. 9 is an enlarged view, taken on the line 9—9 of Fig. 1 and looking in the direction of the arrows.

Fig. 10 is a view in section, taken on the line 10—10 of Fig. 1 and looking in the direction of the arrows.

Fig. 11 is a view in section, showing one of the valves of the fluid system utilized by the present invention.

Fig. 12 is an enlarged detail view, in section, showing the cushioning mechanism provided for the carriage drive.

Fig. 13 is a view in section, taken on the line 13—13 of Fig. 12 and looking in the direction of the arrows.

Fig. 14 is a diagrammatic view of the electrical system used by the present invention.

Fig. 15 is a diagrammatic view of the fluid system used by the present invention.

Referring to the above drawings and particularly to Figs. 1 and 2, it will be observed that an elongated table 1 is provided upon which the fabric 2, to be printed upon, is secured in a suitable fashion. At opposite sides of the table 1, rails 3 are secured, these rails being formed of inverted V-shape as illustrated in Figs. 5 and 7, in order that a movable carriage 4 may be suitably positioned and accurately located upon the table. The rails are formed with flanges 3' which are suitably secured to the table and are engaged by rollers 5, mounted upon brackets 6, mounted upon the bottom of the frame of the carriage 4. These brackets 6 are located at the four corners

50 of the frame and the axes of the rollers preferably lie parallel to the angular sides of the track 3 as illustrated in Fig. 7. The foregoing mounting of the carriage upon the rails provides lateral stability for the carriage and insures proper location upon the table.

Within the carriage 4 there is provided a stencil frame 7 which is pivoted at one end upon a pivot shaft 8 carried upon a platform 9 formed upon the carriage 4.

Within the stencil frame 7 (Fig. 3) a stencil box 10 is secured, the stencil box being provided with a stencil 11 of known form by means of which the selective application of color may be made upon the fabric 2. The stencil box may be located upon channels 12 carried by the frame 7 and color 13 may be applied through the stencil by means of paddles 14 and 15 in a manner to be described hereinafter.

In order that the carriage 4 may be advanced along the table to successive printing positions, the carriage is provided with upper and lower guide rods 16, secured to the carriage by means of front and rear brackets 17 (Figs. 2 and 4). Slidably upon the guides 16 is a cross-head 18 formed with sleeves 19 to slide on the guides 16. The cross-head 18 is formed with a boss 20 (Fig. 5) that is formed with a vertical channel within which a vertically slidable plate 21 is received. The boss 20 is also formed with a horizontal channel 22 within which a plate 23 is slidable, the plate 23 being formed with slots 24, receiving pins 25 that are carried by the boss 20, in order that the plate may be suitably guided. The plate 23 is also formed with an angular slot 26 receiving a pin 27 formed on the plate 21. In this fashion, longitudinal movement of the plate 23 will cause vertical movement of the plate 21 between the limits afforded by the extremities of slot 26.

The plate 21 is formed, at its lower extremity, with one or more teeth 28 that are adapted to engage between the rollers 29 carried by links 30 of a chain that is secured to the table at the side of one of the tracks 3. Certain of the links 30 are formed with flanges 31 in order that the chain may be secured effectively in position.

The cross-head 18 is moved slidably along the guides 16 by means of a connecting rod 32 formed with a piston 33 (Fig. 2) received within an elongated cylinder 34. Fluid is introduced into the cylinder 34 through connection 35 at one end of the cylinder and connection 36 at the other end thereof. In this fashion, the piston 33 may be moved to the right as viewed in Fig. 2, and with respect to the carriage, at which time the cross-head 18 is moved on the guides 16. In the next phase of operation, the piston and cross-head are locked with respect to the track and the cylinder moves to the right, advancing the carriage and guides with respect to the cross-head. Inasmuch as movement of the cross-head 18 to the left as viewed in Fig. 4 will first result in the lowering of the teeth 28 to engage the chain 30, continued movement to the left will result in advancing the entire carriage to the right in the desired fashion.

Movement of the carriage to the right as above described is limited by means of a collar 37 (Fig. 4) carried upon a control rod 38, slidably received in bosses 39 formed upon the cross-head 18. A bracket 40 is adjustably mounted upon the guides 16 and secured in position by means of clamping bolts 41. The bracket 40 slidably receives the control rod 38 and serves as a limit against which the collar 37 engages to arrest the movement of the guides 16 with respect to the control rod and cross-head. In the movement of the carriage to the right, as viewed in Figs. 2 and 4, by the application of fluid pressure to the connection 35, the control rod 38 advances along the cross-head 18 and strikes the collar 37, 75

moving the control rod 38 into supplementary cylinder 42 (Fig. 12). Continued movement of the piston in the cylinder 34 advances the control rod 38 into the cylinder 42 to progressively cut off ports 43 and thus restrict the escape of fluid from the left-hand end of the cylinder 34 into the fitting 36. This provides a cushioning effect to absorb the shock of arresting the movement of the carriage.

10 A flow of fluid in the reverse direction, that is, entering the cylinder 34 through the fitting 36 causes a slow return movement of the piston 33 until the cross-head 18 strikes a collar 37' on the control rod 38 to move the control rod to the right as viewed in Fig. 12. This causes the apertures 43 to be opened and ready for the cushioning operation on the next return of the cross-head.

15 The bracket 40 cooperates with a scale 40¹ that is mounted on the carriage and, by means of an indicator arm 40², indicates the movement of the carriage during each cycle of operation. The travel of the carriage can be adjusted by adjusting the position of the bracket 40 as well as the collar 37.

20 Upon initial movement of the piston 33 to the right in the cylinder 34 as viewed in Fig. 2, the pin 27 will be raised by the slot 26 and the teeth 28 will be disengaged from the chain 30. Continued movement of the piston will advance the cross-head 18 along the guide rods 16 to the position illustrated in Fig. 4, at which time the carriage will be maintained in such position during the printing operation by means of a locking 25 pin illustrated in Fig. 9. This locking pin is shown at 44 and is formed with a piston 45 received within a cylinder 46. Fluid may be introduced into the cylinder by means of fittings 47 and 48 in order that the piston 45 may be moved in opposite directions. The pin 44 is provided with a tooth 49 that is adapted to engage between the adjacent rollers of the chain 30 so that the carriage will be locked in the desired position. The chain thus serves as a locating mechanism 30 for the carriage.

35 In order that the mechanism may be sealed effectively against the escape of fluid from the fluid system, the cylinder 46 is provided with a sleeve 50 threadedly engaged therewith, formed with a chamber 51 within which multiple seals 52 may be received. The entire assembly is mounted upon the carriage frame 4 as will be readily apparent. Beneath the seals 52 there is provided a plate 53 having a peripheral groove 54 connected to a discharge fitting 55 that is connected to a sump as hereinafter described. A lower seal 56 is provided beneath the plate 53 to prevent the escape of fluid below the plate. Upon the pin 44 is provided an arm 57 that is adapted to engage and operate a limit switch G as described herein- 40 after.

45 The operation of the locking pin 44 will be described in greater detail hereinafter in connection with the cycle of operation of the machine.

In order that the color 13 may be applied effectively to the stencil by means of the paddles 14 and 15, the paddles are mounted upon rods 58 that are slidably received in sleeves 59 pivoted at 60 on a frame 61. Springs 62 normally urge the paddles downwardly against the stencil 11 and the sleeves 59 are formed with arms 63 that are provided with set screws 64 adapted to engage against stops 65 in order to limit the angular movement of the sleeves 59 about the pivots 60.

50 As will be apparent from Figs. 3 and 8, move-

ment of the frame 61 to the right will locate the paddles in the positions shown in these figures and the paddle 14 will thus apply the color to the stencil. After the frame 61 reaches the extreme right-hand position and its movement is reversed (as will be described in greater detail hereinafter), the paddles will pivot about the pivot pins 60 and the right-hand paddle 18 will apply the color to the stencil during the movement of the frame 61 to the left as viewed in these figures. The paddles thus alternately serve to apply the color to the stencil and remain in parallel relationship during all such operations.

The frame 61 is provided with upper rollers 66 (Fig. 6) and lower rollers 67. Upper rollers ride on a track 68 while rollers 67 engage the lower surface of a track 69. In this fashion, the vertical movement of the frame 61 is limited.

Through rods 70 (Fig. 8) space the frame elements properly and, in order to mount the frame 61 thereon, the through rods are located by means of plates 71, the frame 61 being journaled upon the lower through rod 70 and secured to the side through rods by means of straps 72.

The paddle frame assembly is moved longitudinally along the guides 68 and 69 by means of an endless chain 73 that is connected to the opposite ends of the plates 71, passing over the sprockets 74 and 75. The lower stretch of the chain 73 is received between the guides 68 and 69, as illustrated in Fig. 6.

Sprockets 75 are mounted upon a drive shaft 76 that is driven by means of a sprocket 77 which is driven by a chain 78 (Figs. 1 and 3) that is driven by a drive sprocket 79 mounted upon a shaft 80. The shaft is driven by means of a sprocket 81 that is driven by shafts 82 and 83 which, in turn, are driven by a worm and worm wheel connection 84 that is driven by an electric motor 85.

The forward end of the stencil frame (the right-hand end as viewed in Figs. 1, 2 and 3) is raised and lowered by means of mechanism shown in Fig. 10. This mechanism includes a cylinder 86 that is pivotally carried by the carriage frame 4 at 87 and is supplied with fluid fittings 88 and 89. A piston 90 is slidably mounted within the cylinder 86 and is connected to a connecting rod 91 that is pivotally connected at 92 to the stencil frame 7. A seal and return mechanism may be provided at the upper end of the cylinder as described in connection with the structure shown in Fig. 9 and the details need not be expanded at this point. It will be apparent that, depending upon the application of fluid pressure to either of the fittings 88 and 89, the piston and stencil frame will be raised or lowered. The manner in which this fluid pressure is applied will be described hereinafter.

The rear end of the stencil frame is provided with brackets 93 (Figs. 1 and 2), these brackets being journaled upon the shaft 80 that is supported in eccentrics 94, pivoted at 95 upon brackets 96, carried upon the table 9. The eccentrics 94 are moved about the pivots 95 by means of a piston 97 that is received within a cylinder 98 provided with fittings 99 and 100 which receive fluid in a manner to be described hereinafter. By controlling the application of fluid pressure to opposite sides of the piston 97 the eccentrics 94 may be raised and lowered.

One of the eccentrics 94 is provided with shoulders 101 and 102 to actuate respectively limit switches A and F as will be described in greater detail hereinafter. The eccentric plates 94 and 78

associated mechanism thus provide a means for raising the rear end of the stencil box or frame during predetermined periods in the cycle of operation of the mechanism.

In order that the various operations hereinabove referred to may be accomplished, the present invention utilizes a fluid system which, in the device shown and described herein, consists of an oil system illustrated diagrammatically in Fig. 15 and including a pressure tank or accumulator 103 within which a body of oil 104 is received, a column of air 105 being maintained above the oil. The oil 104 is maintained under pressure by means of a pump 106 driven by an electric motor 107 that is preferably reversible and may be controlled manually so that the tank may be emptied as it becomes oil-bound.

From the tank 103 a pressure line 108 supplies the oil under pressure to a plurality of valves 109, 110, 111 and 112. These valves are all of similar design and are illustrated in Fig. 11 wherein valve 109 is shown as being formed with a casing 113 and a valve rod 114. The valve rod is formed with a central bushing 115 and bushings 116 and 117. Each of the bushings 116 and 117 may be provided with grooves 118 to serve as seals in a manner which will be readily understood.

A reduced portion 119 is thus formed between the bushings 115 and 116 and a reduced portion 120 between the bushings 115 and 117. The valve rod 114 is normally maintained in one position by means of a spring 121 that is seated upon a disc 122 carried by the rod and within a spring seat 123 which is formed in the casing 113. Movement of the valve into the position shown in Fig. 11 is caused by the energization of an electromagnetic coil II as will be described in greater detail hereinafter.

Fluid under pressure is introduced into the casing 113 by means of a conduit 124 and is adapted to be discharged therefrom through either of the conduits 125. Conduits 126 and 127 (Fig. 15) establish communication between the interior of the valve casing and cylinder 98 through the fittings 99 and 100.

It will thus be seen that when the electromagnetic coil II is energized, the valve rod 114 will be moved into the position shown in Fig. 11 and fluid under pressure will flow from the conduit 124 through the reduced portion 119 to the conduit 126. This will cause the piston 97 to be moved to the left as viewed in Fig. 15 and to elevate the rear of the stencil box. When the valve rod 114 is in its normal position, the fluid pressure is introduced through the conduit 127 to cause a movement of the piston 97 in the reverse position to lower the rear of the stencil box. In each such instance, the conduit 126 or 127 which does not receive fluid under pressure is connected to either of the discharge conduits 125 in a manner which will be readily apparent, thus relieving the appropriate side of the piston 97 from fluid pressure.

Connections of the above character are provided for each of the valves 110, 111 and 112, the normal positions of the valve stems of these valves being such that fluid under pressure normally is maintained in conduits 128, 130 and 133, while conduits 129, 131 and 132 are connected to exhaust connections 125. A sump 134 is provided to collect the fluid discharged from the several valves and pump 106 supplies the fluid from such sump to the tank 103 by means of a pipe 135.

The electrical connections by means of which

the fluid system above described may be controlled are illustrated in Fig. 14 wherein a rotary step switch is shown at 136 and provided with a rotor R having three contact arms r , r^1 and r^2 . These arms are spaced equi-distantly about the rotor and are adapted to make connection with conducting segments s , s^1 and s^2 . The segments s and s^1 are connected together by means of a wire 137 and to a source of current by means of a wire 138. The segment s^2 is connected to a stepping relay 139 and to a suitable source of current by means of a wire 140. For purposes of simplification, the source of current is assumed to be grounded in order that the circuits hereinafter described may be conveniently completed. The stepping relay 139 is provided with a drive arrangement by means of which the rotor R may be advanced periodically to successive positions upon successive energization of the stepping switch.

The stepping switch 136 is provided with contacts that are connected in such fashion as to cause the rotor contactors r , r^1 , and r^2 to advance through eight successive positions upon corresponding contacts before completing one cycle of operation.

The stepping switch is provided with a plurality of contacts, twenty-four in all, spaced circumferentially about the switch and arranged in three groups insofar as their functions are concerned. The first group of eight contacts is illustrated as contacts a , b , c , d , e , f , g and h . The second group of contacts is indicated at a^1 , b^1 , c^1 , d^1 , e^1 , f^1 , g^1 , and h^1 . The third group of contacts is shown at a^2 , b^2 , c^2 , d^2 , e^2 , f^2 , g^2 and h^2 .

It will be seen that contacts b , c and d , and contacts f , g and h are connected together.

Contacts b , c and d are connected to relay coil I by means of a wire 141; contacts f , g and h to relay coil II by means of a wire 142; contact c^1 to relay coil V by means of a wire 143; contacts d^1 to relay coil VI by means of a wire 144; and contacts g^1 and h^1 to relay coils III and IV by means of wires 145 and 146, respectively.

Contacts a^2 , b^2 , c^2 , d^2 , e^2 , f^2 , g^2 , and h^2 are connected to the respective limit switches A, B, C, D, E, F, G, and H by means of wires 147, 148, 149, 150, 151, 152, 153 and 154. The relay coils V and VI control a reversing switch R.S. to control the direction of operation of the reversible motor 85 that operates the paddle frame, previously described. The motor 85 is provided with the usual shunt field winding 85¹ and series field winding 85². The detailed connections by means of which the connections for the motor 85 and the aforesaid field windings may be connected to a source of current indicated at 85³ are illustrated in Fig. 14 and need not be described in detail inasmuch as they are conventional connections for circuits of this character.

The operation of the mechanism is as follows: With the rotary switch R in the position illustrated in Fig. 14, switch arm r connects limit switch H to the stepping coil 139 while the carriage and stencil mechanism is advancing along the table toward the next printing position. When it reaches such position, the limit switch H is closed, energizing the coil 139 and stepping the switch arms to the next position at which time arm r is on dead contact a , arm r^1 on dead contact a^1 and arm r^2 on contact a^2 , so that the limit switch A is connected to the coil 139. Since the relay coil III is de-energized, the locating pin 49 is lowered to its normal position by the flow of oil through conduit 133. Moreover, relay coil II is deenergized to cause oil to be supplied to

the conduit 127 so that the rear pivot of the stencil box is lowered.

As soon as the rear pivot of the stencil box is lowered, the shoulder 101 closes the limit switch 5 A to energize the coil 138 and step the arms of the switch R into the next position. In this position, arm r engages contact b to energize relay coil I; arm r^1 engages dead contact b^1 ; and arm r^2 engages contact b^2 to connect the limit switch B with the coil 139. Energization of relay coil I causes the valve 111 to supply fluids under pressure through conduit 131 to fitting 89, causing the front end of the stencil box to be lowered. When the box is lowered, limit switch B is closed again energizing the coil 139 and stepping the switch R to the next position so that the contacts engage the series of c contacts. Arm r thus causes the relay coil I to maintain the front end of the stencil box down while arm r^1 engages contact c^1 to energize the relay coil V and close the circuit of motor 85 to advance the paddle frame steadily over the stencil. Arm r^2 engages contact c^2 thus connecting the limit switch C in circuit with the coil 139 and, when the paddle frame completes its forward motion, limit switch C is closed, again stepping the contacts of switch R into the d position. In such position, arm r engages contact d to continue to energize the relay coil I; arm r^1 engages contact d^1 to energize the relay coil VI to reverse the direction of rotation of the motor 85; and arm r^2 engages contact d^2 to connect limit switch D in circuit with the coil 139. The reversal of the motor 85 brings the paddle frame back to the starting position, closing the limit switch D and again energizing the coil 139 to step the arms of the switch R into the e position. Since contact e is dead, the front end of the stencil box is elevated by reason of the normal position of the valve 111. Contact e^1 is also dead and contact e^2 connects limit switch E with the coil 139. When the front end of the stencil box is elevated, the limit switch E is closed, again stepping the switch R into the f position wherein arm r engages contact f to energize the relay coil II; contact r^1 engages dead contact f^1 and contact r^2 engages contact f^2 to connect the limit switch F to the relay coil 139. Relay coil II and valve 110 cause fluid under pressure to be directed to the cylinder 88 to cause the pivot connection of the box to be elevated to close the limit switch F and step the switch R around to the g position.

In the g position, the arm r engages contact g to maintain the relay coil II energized; the arm r^1 engages contact g^1 to energize relay coil III; and arm r^2 engages contact g^2 to connect the limit switch G to the coil 139. In this position, the rear pivot of the stencil box is maintained elevated by the continued energization of the coil II and the coil III causes the locating pin 49 to be raised. When the pin 49 is raised the limit switch G is closed to advance the switch R to the h position. In this position, the contact r continues to maintain the coil II energized; the arm r^1 engages contact h^1 to energize the relay coil IV, as well as the elongated contact g^1 to continue to energize coil III; and the arm r^2 engages the contact h^2 to connect the limit switch H to the coil 139. In such position, the relay coil IV causes the valve 110 to be actuated to introduce fluid under pressure into the cylinder 84 and thus advance the carriage toward the next printing position.

It will be observed that, after the carriage has reached the desired printing position, and the

limit switch H closed, the contact arm r¹ moves off of the contact h¹ and the coil or relay IV is de-energized. This permits the valve 110 to move to its normal position and to supply fluid under pressure to the left-hand end of the cylinder 34 to advance the cross-head 18 to the right in order that it will be ready for the next operation.

It will thus be apparent that the invention provides a completely automatic mechanism for advancing the stencil along the material to be printed, locating the stencil, applying the ink, raising the stencil and advancing it to the next position.

While the invention has been described with specific reference to the structure described in the attached drawings, it is not to be limited, save as defined in the appended claims.

I claim:

1. Stencil printing mechanism comprising a work supporting surface, a carriage movable along said surface, stencil printing means on said carriage, an assembly comprising a piston element and a cylinder element, means to connect the assembly to the carriage, means on the assembly to engage the supporting surface, and means to introduce a fluid under pressure into the cylinder to move the carriage with respect to the supporting surface.

2. Stencil printing mechanism comprising a work supporting surface, a carriage movable along said surface, stencil printing means on said carriage, an assembly comprising a piston element and a cylinder element, means to connect the assembly to the carriage, means on the assembly to engage the supporting surface, and means to introduce a fluid under pressure into one end of the cylinder to move the carriage with respect to the supporting surface and into the other end of the cylinder to move the said engaging means with respect to the supporting surface.

3. Stencil printing mechanism comprising a work supporting surface, a carriage movable along said surface, stencil printing means on said carriage, an assembly comprising a piston element and a cylinder element, means to connect the assembly to the carriage, means on the assembly to engage the supporting surface, means to lock the carriage with respect to the supporting surface, and means to introduce a fluid under pressure into one end of the cylinder to move the carriage with respect to the supporting surface and into the other end of the cylinder to move the said engaging means with respect to the supporting surface while the lock means locks the carriage with respect to the supporting surface.

4. Stencil printing mechanism comprising a work supporting surface, a carriage movable along said surface, stencil printing means on said carriage, a cylinder on the carriage, a piston and connecting rod in the cylinder, fluid connections on the cylinder to move the piston in opposite directions, and means on the connecting rod to engage the supporting surface.

5. Stencil printing mechanism comprising a work supporting surface, a carriage movable along said surface, stencil printing means on said carriage, an assembly comprising a piston element and a cylinder element, means to connect one element of the assembly fixedly to the carriage, a guide on the carriage, means to mount the other assembly element slidably on the guide, and means carried by the guide to engage the supporting surface.

6. Stencil printing mechanism comprising a work supporting surface, a carriage movable

along said surface, stencil printing means on said carriage, an assembly comprising a piston element and a cylinder element, means to connect one element of the assembly fixedly to the carriage, a guide on the carriage, means to mount the other assembly element slidably on the guide, a vertically slidable member on the guide to engage the supporting surface, and means to actuate the vertically slidable member by the said other assembly element.

7. Stencil printing mechanism comprising a work supporting surface, a carriage movable along said surface, stencil printing means on said carriage, an assembly comprising a piston element and a cylinder element, means to connect one element of the assembly fixedly to the carriage, a guide on the carriage, means to mount the other assembly element slidably on the guide, a crosshead slidable on the guide, a member slideable vertically in the crosshead to move into and out of engagement with the supporting surface, and a connection between the vertically slidable member and the said other assembly element whereby initial movement of the said other assembly element with respect to the guide effects movement of the vertically slidable element with respect to the crosshead and continued movement of the said other assembly element moves the crosshead with respect to the guide.

8. Stencil printing mechanism comprising a work supporting surface, a carriage movable along said surface, stencil printing means on said carriage, a chain secured to the supporting surface, means on the carriage for engaging links of the chain, and means to move the engaging means with respect to the carriage whereby said chain serves as a means for locating the carriage in desired position.

9. Stencil printing mechanism comprising a work supporting surface, a carriage movable along said surface, stencil printing means on said carriage, a circular pitch chain secured to the supporting surface, means on the carriage for engaging links of the chain, and means to move the engaging means with respect to the carriage whereby said chain serves as a means for locking the carriage in desired position.

10. Stencil printing mechanism comprising a work supporting surface, a stencil frame adapted to support a stencil, means to mount the frame on the supporting surface, a squeegee frame mounted on the stencil frame for movement back and forth across the stencil, squeegee elements, spaced fixed pivot means to mount said elements on the frame, and means to mount the elements on the first means with capacity for yielding movement with respect thereto.

11. Stencil printing mechanism comprising a work supporting surface, a stencil frame adapted to support a stencil, means to mount the frame on the supporting surface, a squeegee frame mounted on the stencil frame for movement back and forth across the stencil, squeegee elements, spaced fixed pivot mountings for said elements on said squeegee frame and means for mounting said elements on said pivot mountings yieldably with capacity for independent operating movement.

12. Stencil printing mechanism comprising a work supporting surface, a stencil frame adapted to support a stencil, means to mount the frame on the supporting surface, a squeegee frame mounted on the stencil frame for movement back and forth across the stencil, squeegee elements, spaced fixed pivot mountings for said elements

on said squeegee frame, means for mounting said elements on said pivot mountings with capacity for independent operating movement, and means to limit pivotal movement of said squeegee elements in at least one direction.

13. Stencil printing mechanism comprising a work supporting surface, a stencil frame adapted to support a stencil, means to mount the frame on the supporting surface, a squeegee frame mounted on the stencil frame for movement back and forth across the stencil, squeegee elements, spaced fixed pivot mountings for said elements on said squeegee frame, means for mounting said element on said pivot mountings with capacity for independent operating movement, means to limit pivotal movement of said squeegee elements in at least one direction, and means to urge the squeegee elements toward the stencil.

14. Stencil printing mechanism comprising a work supporting surface, a carriage movable along said surface, stencil printing means on said carriage, an assembly comprising a piston element and a cylinder element, means to connect the assembly to the carriage, means on the assembly to engage the supporting surface, means to introduce a fluid under pressure into the cylinder to move the carriage with respect to the supporting surface, and means to restrict gradually the flow of said fluid at one end of movement of the carriage.

15. Stencil printing mechanism comprising a work supporting surface, a carriage movable along said surface, stencil printing means on said carriage, an assembly comprising a piston element and a cylinder element, means to connect the assembly to the carriage, means on the assembly to engage the supporting surface, means to introduce a fluid under pressure into the cylinder to move the carriage with respect to the

supporting surface, a supplementary cylinder on the cylinder element having a plurality of ports communicating with the cylinder element and a port communicating with a fluid system, a control rod in the supplementary cylinder, and means to actuate the control rod by an element associated with the piston element.

16. Stencil printing mechanism comprising a work supporting surface, a carriage movable along said surface, stencil printing means movable on the carriage, separate fluid operated means to move the carriage and the stencil, a source of fluid under pressure, valve mechanism to control the flow of fluid from the source to the separate means, and selective mechanism to actuate the valve mechanism.

17. Stencil printing mechanism comprising a work supporting surface, a carriage movable along said surface, stencil printing means movable on the carriage, separate fluid operated means to move the carriage and the stencil, a source of fluid under pressure, valve mechanism to control the flow of fluid from the source to the separate means, and selective mechanism controlled by movements of the carriage and frame to actuate the valve mechanism.

18. Stencil printing mechanism comprising a work supporting surface, a carriage movable along said surface, stencil printing means movable on the carriage, separate fluid operated means to move the carriage and the stencil, a source of fluid under pressure, valve mechanism to control the flow of fluid from the source to the separate means, electromagnetic mechanism to actuate the valve mechanism, and means operated by the printing means to control the electromagnetic mechanism.

WARD THORNE.

CERTIFICATE OF CORRECTION.

Patent No. 2,355,930.

August 15, 1944.

WARD THORNE.

It is hereby certified that error appears in the printed specification of the above numbered patent requiring correction as follows: Page 5, second column, line 46, claim 9, for the word "locking" read --locating--; page 6, first column, line 14, claim 13, for "element" read --elements--; and that the said Letters Patent should be read with this correction therein that the same may conform to the record of the case in the Patent Office.

Signed and sealed this 26th day of September, A. D. 1944.

Leslie Frazer

Acting Commissioner of Patents.

on said squeegee frame, means for mounting said elements on said pivot mountings with capacity for independent operating movement, and means to limit pivotal movement of said squeegee elements in at least one direction.

13. Stencil printing mechanism comprising a work supporting surface, a stencil frame adapted to support a stencil, means to mount the frame on the supporting surface, a squeegee frame mounted on the stencil frame for movement back and forth across the stencil, squeegee elements, spaced fixed pivot mountings for said elements on said squeegee frame, means for mounting said element on said pivot mountings with capacity for independent operating movement, means to limit pivotal movement of said squeegee elements in at least one direction, and means to urge the squeegee elements toward the stencil.

14. Stencil printing mechanism comprising a work supporting surface, a carriage movable along said surface, stencil printing means on said carriage, an assembly comprising a piston element and a cylinder element, means to connect the assembly to the carriage, means on the assembly to engage the supporting surface, means to introduce a fluid under pressure into the cylinder to move the carriage with respect to the supporting surface, and means to restrict gradually the flow of said fluid at one end of movement of the carriage.

15. Stencil printing mechanism comprising a work supporting surface, a carriage movable along said surface, stencil printing means on said carriage, an assembly comprising a piston element and a cylinder element, means to connect the assembly to the carriage, means on the assembly to engage the supporting surface, means to introduce a fluid under pressure into the cylinder to move the carriage with respect to the

supporting surface, a supplementary cylinder on the cylinder element having a plurality of ports communicating with the cylinder element and a port communicating with a fluid system, a control rod in the supplementary cylinder, and means to actuate the control rod by an element associated with the piston element.

16. Stencil printing mechanism comprising a work supporting surface, a carriage movable along said surface, stencil printing means movable on the carriage, separate fluid operated means to move the carriage and the stencil, a source of fluid under pressure, valve mechanism to control the flow of fluid from the source to the separate means, and selective mechanism to actuate the valve mechanism.

17. Stencil printing mechanism comprising a work supporting surface, a carriage movable along said surface, stencil printing means movable on the carriage, separate fluid operated means to move the carriage and the stencil, a source of fluid under pressure, valve mechanism to control the flow of fluid from the source to the separate means, and selective mechanism controlled by movements of the carriage and frame to actuate the valve mechanism.

18. Stencil printing mechanism comprising a work supporting surface, a carriage movable along said surface, stencil printing means movable on the carriage, separate fluid operated means to move the carriage and the stencil, a source of fluid under pressure, valve mechanism to control the flow of fluid from the source to the separate means, electromagnetic mechanism to actuate the valve mechanism, and means operated by the printing means to control the electromagnetic mechanism.
